LANTERN

Carl Metz, Philadelphia, Pa., assignor, by mesne assignments, to Frederick McOwen, Philadelphia, Pa.

Application August 16, 1932, Serial No. 629,028
Renewed March 2, 1935

5 Claims. (Cl. 240—38)

This invention relates to lanterns and particularly to that class thereof designed for use in signaling on railways.

I have various objects in mind, to be carried out by the improvements in lanterns, constituting my invention. One of these objects is to provide a lantern construction, which, while lending itself practically to sheet metal stamping operations, will afford a more even draft through the lantern, in connection with supplying air to the burning wick and in the discharge of the air from the upper part of the lantern, regardless of the force of air blown against the outside of the lantern. In this connection, a further object is to provide forms of baffle construction for the air inlet and outlet parts, of the lantern, which will prevent direct incoming or through drafts, which interfere with the natural circulation of air within a lighted lantern.

A further object is to take advantage of the heat in the oil font, which accumulates during the burning of the wick, and to provide a construction of walls and the positioning of air passages therethrough, which will cause the incoming air to remain longer in the vicinity of the heated font, as it is passing through the walled passages, giving the air a better chance to get warmer from these walls. My object in thus increasing the temperature of the air in the lower part of the lantern, is to create a greater difference in air temperature between the lower and upper areas within the globe and the hood of the lantern, which will result in a better and more controlled flow of air through the lantern, effecting a more even draft.

Another object is to provide a removable globe holder at the top of the lantern, which can be quickly sprung into place and locked there in a changeable position, for self-adjustment, as it is seated upon the globe, when the lantern lid is snapped down into place.

A further object is to provide with the globe holder, a form of cylindrical windshield, which will give an upward direction to cooling and incoming air, to pass in and out of the lantern top, to reduce the temperature thereof, to make a greater difference in temperature between the bottom and the top of the lantern, thus further amplifying this difference of temperature, which is increased below as has been stated, and thus decreased above, affording a still more improved and controlled draft through the lantern.

Another object is to provide a form of globe holder adapted to slidingly fit within the hood of the lantern, having at the usual upper opening,

a winged baffle piece, fixed to the globe holder and extending across said opening. This baffle piece, I desire to have formed with box-shaped ends, extending to the outer top edge of the globe holder and while forming an anchorage for the usual compression spring above, will also be adapted to co-ordinate with studs fixed to and extending within the hood of the lantern, having these studs positioned diametrically opposite one another, affording, with the box-shaped ends of the baffle piece, a kind of bayonet locking arrangement, at the same time permitting a freedom of action to the compression spring in automatically adjusting the globe holder in seating relation to the globe. Further, I desire to afford with such bayonet locking arrangement, a construction permitting of a quick and easy release of the globe holder, for cleaning purposes, as well as affording a quick and easy replacement of the globe holder, with the hood, prior to snapping the lantern hood down, with the globe in place.

With these and other objects, which will hereinafter appear, my invention resides in certain construction, one embodiment of which is illustrated in the drawings, and is hereinafter described. The use and operation of the construction is explained and what I claim is set forth.

In the drawings,

Figure 1 is an elevation of a lantern embodying my invention.

Figure 2 is a perspective view of the globe holder.

Figure 3 is a sectional plan taken on the line 3—3 of Figure 1.

Figure 4 is a section taken on the line 4—4, of Figure 3.

Figure 5 is a section taken on the line 5—5, of Figure 3.

In the figures, the lantern 10 is shown to have a cage 11, with upright ribs 12, which are surmounted by a top ring 13, to which is hinged and releasably locked, a lantern top 14, having a hood 15 and a skirt 16. Fixed to oppositely disposed ribs 12, are the bail ears 17, to which is loosely attached the bail 18. Engaging all the ribs 12 is the bottom ring 19, the guard ring 20 and the angle ring 21, which has a horizontal flange 22, to which are fixed the ribs 12. 23 is the vertical leg of the angle ring 21, forming a band fixed between the shoulder 24 and the outstanding bead 25, of the outer cylindrical wall 26, of the lower portion 27, of the lantern 10. Below the shoulder 24, is the outstanding bead 28, above which is a series of holes 29, passing through the wall 26. Below the bead 28, is the skirt portion 55

30, of the wall 26. An inverted closure cap 31, forms the bottom of the lantern portion 27, and has a rim portion 32, fitting tightly about the skirt portion 30, of the wall 26. The cap 31 has 5 a flat wall portion 33, a cylindrical wall portion 34, and a floor portion 35. The top edge of the wall 26, is turned outward and is engaged by the rim portion 36, of the globe seat member 37, having a globe seat 38, below the rim portion 36, 10 upon which rests the glass globe 39. Depending from the inner edge of the seat 38, is the cylindrical wall portion 40, of the member 37. The lower edge 41, of the wall portion 40, is turned in to be about the same diameter as that of the wall 15 portion 34. Just below the globe seat 38, the wall portion 40 has a series of holes 42, therethrough. Below these holes 42, is the rim 43, of the oil font 44, of the lamp. This oil font 44 has a closure 45, a bottom 46, and a side wall 47, 20 which fits within the edge 41 and rests slidingly within the wall portion 34, of the cap 31, and upon the floor portion 35. 48 is the wick of the lamp, and 49 is the wick wheel, with a stem 50, passing through the slot 51, in the wall 26, to 25 come below the globe seat 38.

Between the wall 26 and the font wall 47, is the flanged, cylindrical wall 52, which rests upon the flat wall portion 33 and engages the upper bead 25. This wall 52 is positioned midway between the wall 26 and the font wall 47, and has a series of holes 53, passing through its lower portion. 30

Considering the formation of the globe holder 54, which slidingly engages the inside of the hood 15, the outer wall 55 has a skirt portion 56, merging into a conical portion 57, which merges into an upper portion 58, having an inclined inner flanged portion 59, surrounding the opening 60, in the top of the globe holder 54. 35

40 Reaching across the opening 60, is the winged baffle piece 61, having divergently inclined wings 62, depending from the bar portions 63, between which is the longitudinal open space 64. The wings 62 are below the flange 59. The box-shaped 45 ends 65, of the baffle piece 61, each being shaped having opposite triangular sides 66 and 67, integral with a top 68, are open below where the sides 66 and 67 come in contact with the flange 59. Each wall 66 and 67 is notched below at 69 50 and 70, respectively, to be engaged by the bottom coil, of the spring 71, and each wall 67 is cut away enough at 72, to permit a stud 73, fixed in the wall of the hood, to project within a box-shaped end 65. The baffle piece 61 is securely locked on 55 top of the flange 59 by means of the tongues 74, which are bent up under the flange 59, at each end. The lower edge 75, of the wall 56 is flared out a little and is engaged by the lower part of the cylindrical windshield portion 76, to form the rim 60 77, of the globe holder 54. Above the rim 77, is a series of holes 78, passing through the wall 56. The windshield portion 76 has a globe seat 79, resting upon the globe 39. Merging into the inner edge of the seat 79, is the cylindrical baffle 65 portion 80, terminating above in an inturned edge 81, annularly spaced from the conical portion 57 of the globe holder 54. The hood 15, has an outstanding bead 82, above which is the group of holes 83 passing through the sides of the hood 70 75 15. The top 84 of the hood 15 is made convex, and has the top coils of the spring 71 bearing up against it, inside.

In use, considering the paths of the air currents into and through the lantern, when the same is lit, with the wick burning, air enters the holes 29,

in the outer wall 26, of the lower portion 27 of the lantern 10, and then descends toward the flat portion 33 and enters the holes 53 in the intermediate wall 52. Next it ascends between this wall 52 and the wall 47, of the oil font, and passes up through the holes 42, where it enters within the globe 39. During the movement of the air between the outer wall 26 and the font wall 47, it becomes heated from these walls in lower portion 27, of the lantern 10, and at the same time, 10 the wall 52 serves as a baffle to any air forcibly blown through the holes 29. At the same time, the limited passage to the air, afforded by the holes 53, acts to hold the air between the baffle wall 52 and the wall 26, until it has time to pass 15 through the holes 53, thus checking any sudden draft before the air reaches the holes 42, and enters within the globe 39.

At the top of the lantern 10, the heated air passes through the globe holder 54, and out at the 20 opening 60, therein, entering the hood 15, and passing out through the holes 83. As the air passes through the globe holder opening 60, it passes also by baffle piece 61, and through its long opening 64. The baffle wings 62 and the conical flange 59, serve to check any sudden down currents of air, blown in through the holes 83. Additional up-flowing air currents within the globe holder 54, are afforded by the construction including the baffle wall 83 and the annular space 30 between the wall edge 81 and the conical portion 57, of the wall 56, in a manner, to increase the velocity of the air passing by the edge 81, after it enters the space between the walls 56 and 83, coming in through the holes 78. The space surrounding the wall edge 81, forms a sort of Venturi throat to increase the velocity of the upwardly moving air and improves the draft up through the upper part of the globe holder 54. Air entering the holes 78, if forcibly blown in, tends to 40 accelerate the velocity of the air through the Venturi throat and therefore increases the resistance of the air currents, so increased, against any down draft tendency. Then there is a cooling effect afforded by fresh cool air coming into 45 the holes 78 and passing up through the parts as just explained. This cooling effect is beneficial, inasmuch as it makes for a greater difference of temperature between the air within, and at the bottom of the globe 39, and the air at the top. 50 By increasing the temperature at the lower part of the globe 39, and decreasing the temperature at the upper part, I have improved the natural draft through the lantern and made it more steady and even, while at the same time, I have 55 checked adverse drafts by means of the baffle walls 52, below, and 80 above as against strong air currents by wind or otherwise, blowing past the lantern. It will be observed, that with this better control of the natural air draft through the 60 lantern, I have improved the lantern for signal purposes, permitting of swinging the lantern through the air without disturbing its natural internal drafts.

Referring again to the globe holder 54, but 65 this time to the facilities afforded for easily positioning and releasing the same, in relation to the hood 15, as well as for securely locking the globe holder in place, when about to assemble the globe holder 54, with the hood 15, after having cleaned the same and the hood 15, let us assume that the lantern lid 14 is open. We begin by entering the spring 71 into the hood 15, and slip the wall portion 58, into engagement with the inside of the wall of the hood 15, having the 75

box-shaped ends 65, of the baffle piece 61, out of line with the studs 73. Then upon forcing the holder 54 further in, until the outer part, of the flange 59, strikes the studs 73, the holder is held in this position and turned until the openings 72, have passed the studs 73, and the side walls 66, strike the studs 73. Then, with the spring 71 being compressed, upon releasing the hold upon the globe holder 54, the spring will force the same outward, and bring the top walls 68, of the box ends 65, up against the studs 73, holding this locking engagement with the studs 73, on account of the same being between the side walls 66 and 67, of the box ends 65. Next, when I shut the lid 14 down, having the globe in place, and having engaged the globe top, to come against the seat 79 and within the flange 71, there will be an up-movement between the wall of the hood 15 and the holder 54, as the lid 14 is snapped in place, so that the tops 68, of the ends 65, will become spaced from the studs 73, leaving the studs relatively, about midway between the tops 68, and the flange 59, so as to engage either of the side walls 66 or 67, to stop any turning of the globe holder 54, within the hood 15, after the lid 14 has been snapped down, in place upon the ring 13. The steps in the operation of assembly and locking of the holder 54 within the hood 15, are taken in the reverse order for removing the holder 54, from the hood 15, for cleaning or any other purpose.

While I have shown and described but one embodiment of my invention, changes in the forms of construction can be made without departing from the spirit and scope of this invention. I wish therefore, to include all forms which come within the purview of the following claims.

I claim:

1. A lantern, having a lamp font, said lantern including in combination, a lamp font receptacle, comprising an outer cylindrical wall, an inverted cap closing the bottom of said wall, a globe seating member, attached to the upper part of said wall, and extending down as a receptacle wall within the same to fit around said lamp font, a skirt portion to said cylindrical wall spaced from the said receptacle wall, a bottom portion to said cap, a cylindrical baffle wall between said outer cylindrical wall and said font, separating the space therebetween into two cylindrical spaces, concentric with said font, one space being on the inside and the other on the outside of said baffle wall, said baffle wall being in contact above, with said outer cylindrical wall, and being in contact below with a portion of said cap, there being air openings in said outer cylindrical wall, in said baffle wall, and in said globe seating member, the openings in said baffle wall being positioned in its lower portion, the openings in said outer cylindrical wall being above the openings in said baffle wall, and the openings in said skirt portion, of said globe seating member, being in the upper part of said skirt portion, above said font, resting within said receptacle.

2. A lantern, including a globe, a spring and a top, having a perforated hood, said lantern having in combination, a globe holder, comprising an outer cylindrical wall, a skirt portion to said wall, a hood fitting portion to said wall, a conical portion to said wall, joining said hood fitting portion and said skirt portion, an inturned flange at the top of said hood fitting portion, said flange being fixed to said spring and a cylindrical baffle wall, spaced from said skirt portion, and joined below to said skirt portion, the upper edge of said baffle wall being spaced within said conical portion and forming therewith an annular Venturi throat, there being air inlets in said skirt portion, and releasable locking means for securing said globe holder to said hood.

3. In a lantern, a globe holder having in combination therewith an outer wall having a lower and an upper portion of less diameter than the lower portion, an inclined portion forming a conical section to said outer wall, joining the said upper and lower portions, said lower portion having openings therein, an inner upright wall connecting at its lower portion with the lower part of said outer wall, and extending upward within said outer wall and spaced therefrom, the upper part of said inner upright wall being inwardly bent and adjoining said inclined portion, to form therewith a Venturi throat circumferentially, for the upward passage of air within said globe holder.

4. A lantern, including a globe, a compression spring and a perforated hood, said lantern having in combination a globe holder with an upper inturned flange with an opening in said flange, said spring being attached to said globe holder, a baffle piece extending across said opening and fixed to said globe holder and a locking means co-ordinating with said spring connected with said baffle piece and said hood, said baffle piece comprising, spaced bar members, extending across said opening, end portions to said piece, extending over said inturned flange, baffle wings depending from said bar members, securing lips on said baffle piece, positioned at the ends of the space between said bar members, and binding said baffle piece to said inturned flange.

5. A lantern, including a globe, a compression spring and a perforated hood, said lantern having in combination, a globe holder with an upper in-turned flange with an opening in said flange, said spring being attached to said globe holder, a baffle piece extending across said opening and fixed to said globe holder, and a locking means co-ordinating with said spring connected with said baffle piece and said hood, said locking means comprising studs diametrically positioned, fixed to and projecting within said hood, box-shaped ends to said baffle piece adapted to engage said studs, there being an opening in the side of each of said box-shaped ends, through which a stud passes within said end.

CARL METZ.
